UNITED STATES PATENT OFFICE

MEYER HORWITZ, OF BALTIMORE, MARYLAND

DESIGN FOR A COIN CONTROLLED GAME APPARATUS

Application filed February 10, 1932. Serial No. 42,798. Term of patent 7 years.

To all whom it may concern:

Be it known that I, MEYER HORWITZ, a citizen of the United States, residing at 2221 East Fairmount Avenue, in the city of Baltimore and State of Maryland, have invented a new, original, and ornamental Design for Coin Controlled Game Apparatus, of which the following is a specification, reference being had to the accompanying drawing, forming a part thereof.

The figure is a perspective view of a coin controlled game apparatus, showing my new design.

I claim:

The ornamental design for a coin controlled game apparatus, as shown.

MEYER HORWITZ.
